SELECTOR MECHANISM FOR RADIO APPARATUS

Joseph C. Clark, Merchantville, N. J., assignor to
Radio Corporation of America, a corporation
of Delaware

Application December 27, 1943, Serial No. 515,857

29 Claims. (Cl. 192—142)

1

My present invention relates to a selector mechanism for radio apparatus, and more particularly to mechanism for automatically and selectively adjusting the tuning device of a radio receiver or the like to preset positions whereby one of a number of predetermined radio transmitting stations may be tuned-in rapidly and accurately from a remote control point.

An object of the invention is to provide a motor-actuated selector mechanism, operation of which is initiated at a remote point by rotary switch means or a series of push-buttons.

Another object of the invention is to provide a selector mechanism of the type above mentioned which may be conditioned from a remote point to provide manual tuning either at the receiver or at the remote point.

A further object is to provide a selector mechanism capable of automatic operation for effecting adjustment of a controlled device to a limited number of predetermined fixed positions, and capable also of manual operation for effecting adjustment of the device to a multiplicity of positions, the mechanism being further provided with means at a remote point for selecting the manner of operation and then carrying out the selected manner of operation from the remote point.

A still further object is to provide automatic mechanism for selectively adjusting a device to one of a plurality of predetermined positions, the mechanism comprising a plurality of stop-discs mechanically coupled to the device each corresponding to one of said positions, a plurality of locking keys each adapted to cooperate with a corresponding stop-disc, key selector means operative to select the particular key to be effective in determining the desired adjusted position of the device, key actuating means for moving the selected key into engagement with its corresponding stop-disc, an electric motor, a master gear driven by the motor, means for individually coupling the key selector means, the key actuating means and the stop-discs to the master gear to be driven therefrom, and means for making the individual coupling means effective in proper sequence whereby the key selector means is first operated to a predetermined position to select a particular key, after which the key actuating means is operated to cause the selected key to move into engagement with its associated stop-disc, and then said stop-disc is moved into locking engagement with the selected key at which time the device will assume its predetermined adjusted position.

2

Another object is to provide a solenoid-actuated gear for effecting the coupling between the motor-actuated master gear and the several means driven therefrom, the several solenoids being included in an electro-mechanical system which functions to effect the proper sequence of operation.

Still a further object is to provide a selector mechanism which is capable of adjusting the receiver to a plurality of predetermined stations even though they are included in different frequency bands, band-switching being accomplished automatically in going from a previously tuned-in station in one band to a desired predetermined station in another band.

And, still a further object of the invention is to provide a selector mechanism of the type mentioned which is positive in action, simple to operate, of compact construction, and of light weight, such that it may be suitable for use with aircraft receivers where these characteristics are especially important.

The novel features characteristic of my invention are set forth with particularity in the appended claims. The invention itself, however, as to both its organization and mode of operation together with further objects and advantages thereof, will best be understood by reference to the following description taken in connection with the accompanying drawing, in which:

Fig. 1 is a view in perspective of the automatic selector mechanism embodying the present invention;

Fig. 2 is a cross-sectional view taken along the line 2—2 of Fig. 1;

Fig. 3 is a view, partly in section, taken along the line 3—3 of Fig. 2;

Fig. 4 is a view in cross-section of the selector disc stack and certain related parts;

Fig. 5 is an end view of the selector stack as viewed from the right of Fig. 4;

Figs. 6A and 6B are, respectively, front elevational and end views of the selector drum;

Figs. 7A to 7C show the relative disposition of a selector disc, a key lever, selector drum and slide bar during a cycle of operation of the selector mechanism;

Fig. 8 is an end view of the selector unit, taken along line 8—8 of Fig. 2;

Fig. 9 is an end view of the selector unit, taken along the line 9—9 of Fig. 2;

Fig. 10 is a side view of the selector unit as seen from the left in Fig. 3;

Fig. 11 is a view in front elevation showing

diagrammatically the shiftable solenoid gears in position relative to the ring gear;

Fig. 12 is a side view of Fig. 11, showing certain additional elements under the control of the various solenoids;

Fig. 13 is a view showing the mechanism for oscillating the disc stack assembly;

Fig. 14 is a top view of the selector device with certain parts removed;

Fig. 15 is a view in cross-section taken on line 15-15 of Fig. 14 showing details of construction of the slide assembly;

Fig. 16 is a front view of the manual disc and shift lever assembly, as viewed from the right of Fig. 10;

Fig. 17 is a side view of the assembly shown in Fig. 16 with certain parts added and other parts shown diagrammatically for the sake of simplicity; and

Fig. 18 is a schematic diagram of the electrical circuit utilized in the operation of the automatic selector device.

In general, the selector mechanism of the present invention comprises a stack of individually-adjustable selector discs corresponding to the number of stations to be automatically tuned, the disc stack being mechanically coupled as a unitary device to the tuning device of the receiver to be controlled; a corresponding number of pivoted keys each of which is adapted upon actuation to lock the disc stack in a predetermined angular position; and a selector drum for determining the particular locking key to be actuated.

Each disc is provided at one point in its periphery with a suitably shaped notch, the angular setting of which determines the position to which the tuning device is to be automatically actuated. The keys are pivoted on a common shaft, each having one end shaped to engage the notch of its associated disc, while the other end is disposed in the path of a projection on the surface of the selector drum. There are as many projections on the drum as there are keys, and they are spaced apart in an axial direction corresponding to the spacing between the key ends and equally in a radial direction around the drum.

The selector drum is first rotated to one of a plurality of adjusted positions corresponding to a particular switch position or push-button at the remote point. In such adjusted position, one of the drum projections will move its corresponding key to a slightly raised position. A slide bar is then actuated to lift the key still further so that its shaped end rides on the periphery of its corresponding disc. As long as the key is in the latter position, the stack disc assembly is caused, by suitable means, to oscillate back and forth until the shaped end of the key drops into the disc notch. When this occurs the means for oscillating the disc assembly is made ineffective and, due to further movement of the slide bar, the shaped end of the key is forced home into the disc notch. The disc assembly will then be in a position of rest, and the tuning device being mechanically coupled thereto will have been moved to its preset position of adjustment.

In addition to the above described automatic operation, suitable means are provided whereby the selector mechanism is made ineffective so that the tuning device may be actuated, either locally or from a remote point, to any desired position by manual control, means also being provided at the remote point for switching to the desired operating band.

Referring now to Fig. 1 which shows the general appearance of the device, it is seen to comprise a casting 1 to the rear of which there is attached the unit 2, which represents the selector device per se. To the rear of the selector unit there is mechanically coupled by suitable means indicated generally by the dash line 3 a tuning device 4 of the receiver to be controlled which may be a variable condenser, a variometer, a variable inductance of the moving core type, etc. From the front of the casting there protrudes a shaft which carries a manual tuning knob or hand wheel 5 so that the receiver may be tuned locally by the operator. From the lower end of the side wall there extends a bushing 6 which houses a spline to which a flexible shaft 6' is adapted for connection so that manual tuning may be accomplished from a remote point. A rocker shaft 7 extends between side walls of the casting, and a lever 8 is keyed to the extended end at the left for the purpose of making preliminary adjustments in the selector unit, as will be described hereinafter. A multi-conductor cable 9 extends from the rear of the selector unit and terminates in a control box at a remote point. Formed integrally with the casting or otherwise attached thereto are a plurality of tapped portions 10 which enable the selector device to be mounted in position, for example behind the front panel of the receiver. Shown also in this figure are four solenoids to be more fully described later but which for the present will be designated as follows: 11, the oscillating solenoid; 12, the selector drum solenoid; 13, the segregating or slide bar solenoid; and 14, the band-switch solenoid.

In Fig. 2 the selector unit 2 is shown to comprise a front plate 26, an intermediate or second plate 15 and a rear plate 16 disposed in parallel spaced relation and within which suitable bearings are formed for receiving a main shaft 17 which extends somewhat beyond the end plates. The second plate is supported from the rear of the casting 1 by a plurality of bolts, one of which is shown at 15'. The shaft 17 is adapted to have mounted thereon, between the second and rear plates 15, 16, the selector disc stack assembly shown generally at 18 to be described more fully in connection with Figs. 4 and 5.

The extended end of shaft 17, at the right in Fig. 2, has connected thereto fork assembly 19, shown more particularly in Fig. 9, consisting of a casting having a rigid arm 19' and a resilient arm 19'' urged together by a spring 20 for clamping a pin 4' projecting from an arm 4'' affixed to the variable member of the condenser. The action of the resilient member pressing pin 4' against the rigid member 19' of the fork eliminates back-lash or lost motion between the selector and the condenser. This construction, as well as assuring exact one-to-one movement between the selector and the condenser, permits a reasonable amount of misalignment between them, which is unavoidable in certain types of installations.

The extended end of the shaft, at the left, carries a gear 21 which meshes with a second gear 22 affixed to a sleeve 23, to the forward end of which there is affixed a circular indicator dial 24 having station or frequency calibrations thereon. The tuning condenser employed is capable of rotation through only 180 degrees. In order to utilize the full scale of dial 24 and to spread the graduations thereon as far as possible, the dial is geared up with respect to the condenser in a ratio of 15 to 8, through the medium of gear

22 having 32 teeth meshing with pinion 21 having 60 teeth.

Concentrically arranged with respect to the dial 24 is a second dial 25 which serves to indicate the band to which the receiver is set. Mounted on the front plate 26 are the above mentioned solenoids 11 to 14. Disposed between the plates 15 and 26 is a fixed bearing on which there is rotatably mounted a ring gear 27 adapted to be driven through a suitable gear train from an electric motor which serves to operate the selector mechanism.

In Fig. 3 the ring gear 27, shown in front elevation and partly in section, is driven through a gear train 28 to 31 from a uni-directional electric motor (not shown). As best shown in Fig. 14, gear 31 is mounted between plates 15 and 26 on the end of a shaft 32 which has its other end journaled in rear plate 16. Shaft 32 is motor-driven through the medium of a worm gear 32' mounted thereon in mesh with a worm 32" carried on the motor shaft.

A stationary disc member 27' affixed to plate 15 and arranged in concentric relation with the shaft 17 serves as the bearing for the ring gear. In order to provide almost frictionless contact between the gear and disc member, the bearing surfaces thereof are formed as a raceway 33 containing the ball bearings 34. A rim member 35 (Figs. 2 and 3) is attached to the stationary disc member 27' for retaining the ball bearings within the raceway.

Disposed around the periphery of the gear 27 are the gears 36, 37, 38 and 39 which are associated respectively with the solenoids 11, 12, 13 and 14. The solenoids being mounted forwardly of the ring gear 27 on plate 26, they will not be seen in the view of Fig. 3, but in order that they may be shown in their relative positions and in association with their respective gears, they are represented in this figure by the dotted circles. The gears 36-39 normally do not mesh with the ring gear, being disposed in the space between plate 26 and gear 27 as shown in Fig. 2 for the solenoid gear 38. Upon the energization of the solenoids, however, at predetermined times in the cycle of operation, the respective gears will each be forced into meshing relation with the ring gear.

Shown also in Fig. 3 in dotted outline is an end view of the selector disc assembly 18, a key lever 40 and a selector drum 41, now to be described more fully in connection with Figs. 4 to 6.

The disc assembly 18 comprises a stack of discs 42, the number thereof being equal to the number of stations for which it is desired to provide automatic tuning. There are ten such discs shown in the present embodiment, although it will be understood that the number can be varied to suit the requirements of the installation.

The several selector discs are mounted on individual bushings 43 which are clamped against rotation on the shaft 17. Also clamped to the shaft and extending from between adjacent bushings to the periphery of adjacent discs are thin wafers or washers 44. To the right of the disc stack is a disc 45 of larger diameter and to the right of the latter disc there is positioned a bowed dish-like spring 46. With this construction the discs of the stack assembly are free to turn radially when not compressed axially by the pressure exerted by the spring 46, but are clamped in position rigidly by this spring under normal conditions. The purpose of the wafers 44 separating each of discs is to prevent the rotation of

any one disc from affecting the position of an adjacent disc.

At the left end of the stack is a disc 47 of the same diameter as discs 42 which is rigidly attached to the shaft 17 by key means or otherwise. A shiftable disc assembly 47', employed to condition the mechanism for manual tuning is mounted to the left of the end disc on a reduced portion of shaft 17. An elongated slot 48 is formed in the surface of disc 47 to accomplish this function as will be described later.

A gear 49 provided with an internally threaded hub 50 is adapted to be screwed home onto the threaded portion 51 of shaft 17 in order that the bushings and the washers may be clamped together rigidly as a unit. In a manner to be explained hereinafter a pair of rollers 52 may be moved to the right as viewed in Figs. 2 and 4 to apply pressure to the larger disc 45 to urge it to the right against the action of spring 46 so that any one of the discs 42 may be rotated to a desired angular setting. Each selector disc is provided at one point in its periphery with a V-shaped notch 53, shown in Figs. 2 and 5, the particular radial setting of which determines the angular position of the device to be adjusted.

The shaft 17 is provided with a reduced portion 54 on which there is seated a gear 55 which is driven by suitable means to oscillate the stack assembly 18. Interposed between the gear 55 and the stack assembly is a friction drive device constituted by a plate member 56 attached to gear 55 and a cooperating plate member 57 attached to the gear 49.

Pivotedly mounted on a shaft 58 which extends in parallel relation with the disc assembly shaft 17 are the key levers 40 above mentioned, one for each selector disc, corresponding levers and discs being aligned with one another in a vertical plane. The key levers each have the configuration shown for example in Figs. 7A to 7C, one end being provided with a head portion 59 and the other end with a tail portion 60. It will be noted that the aperture 61 in the key lever through which the shaft extends is not circular but elongated somewhat in a direction transverse to the length of the key and wedge-shaped for a purpose to be described later.

The selector drum 41 is positioned just below the tail ends 60 of the key levers, extending transversely and in parallel relation with the shafts 17 and 58. A side elevation of the drum is shown in Fig. 6A and a front view in Fig. 6B from which it will be seen that there are arranged on the surface thereof a series of pins or projections 62 which are spaced in an axial direction corresponding to the spacing between the key levers, and spaced apart equally in a radial direction, the several pins forming a spiral around the drum. There are 11 such pins, 10 of which are effective to provide automatic operation, and the 11th, the one on the extreme left in Fig. 6A referenced 62', being used to effect manual control in a manner to be described.

The drum is provided on opposite sides with trunnions 41' which are adapted to fit into bearings formed in the intermediate and rear plates 15, 16 of the selector unit so that the drum may be rotated about its axis when actuated by suitable driving means. Mounted on the left-hand trunnion (Fig. 10) for rotation with the drum is a 11-position detent wheel 63 (corresponding to 10 automatic positions and a manual position) which, in cooperation with a pivoted detent lever 63' urged into engagement with one of the wheel

detents by a spring 63" (Fig. 9), is effective to maintain the drum in any position to which it may be rotated.

In Figs. 7A to 7C are illustrated the successive positions of a selector disc 42 and of its corresponding key lever and selector pin during a cycle of operation. In the position shown in Fig. 7A the tail end 60 of the lever will ride on the surface of the drum and the head end 59 will be elevated slightly above the periphery of the disc by reason of pressure applied to the lower part of the lever by a leaf spring 64. Assume now that the drum is rotated in the direction of the arrow to the position shown in Fig. 7B. In moving to this position the pin 62 will apply a force to the tail end of the key lever which will rock slightly in a clockwise direction about its shaft. At this time a knife-edged slide bar or segregating bar 65 is brought up to bear against the underside of the tail end of the lever with considerable force, overpowering spring 64, and causing the particular key which has been segregated from the others to rock still further. This causes the head end of the key to approach its particular selector disc, either coming to rest somewhere on the periphery of the disc or forcing itself into the V-shaped notch, if the disc stack were already turned to nearly the correct position. With the key head falling on the periphery of the disc the disc stack is oscillated back and forth by means hereinafter to be described, until the notch 53 of the particular disc arrives underneath or in registry with the key head, causing the lever to rock still further about its pivot, at which time the oscillating means will cease to function. Due to the continued pressure of the slide bar, however, the head end of the key lever will be wedged into the disc notch, 53, and the mid-section of the lever will be raised slightly to permit the lower portion of the aperture 61 to firmly hug the shaft. In the home position of the disc shown in Fig. 7C the disc will be locked against rotation and in the angular position for which it was set.

The mechanism for actuating the segregating bar 65 will now be described in connection with Figs. 8, 9 and 10, the first two being views taken respectively along the lines 8-8 and 9-9 in Fig. 2, and the third being a view looked at from the left in Fig. 3. Pivoted at 66 to the outer surfaces of both the second and rear plates 15 and 16 are a pair of arms 67, 68, respectively, which are of similar configuration, except for an arcuate extension 69 on the front arm 67. The arms are provided each with an upstanding portion 70 to which a force is adapted to be applied for moving the arms downwardly, through an arc about their pivotal points 66, against the action of a pair of springs 71 only one of which is shown in Fig. 8. Carried by the arms and extending therebetween through an arcuate cut-out 72 in each of the plates is the segregating or slide bar 65 previously mentioned.

Suitably journaled on the outer surfaces of plates 15, 16 are a pair of gears 73, 74, respectively, which are adapted to be driven simultaneously from the ring gear when the slide bar solenoid 13 is energized. Each gear carries a cam 75, the two being similarly shaped, as shown, and phased to coact simultaneously with the upright extensions 70 of the slide bar carrier arms. The gear 74 on the rear plate carries in addition a crown cam 76 provided at one portion of its circumference with a sloped notch or depression 77. With the crown cam in the position shown in Fig. 9, which is its position of rest, the notch will receive a

pin 78 which is adapted upon being lifted out of the notch by rotation of the crown cam to close a switch 79 connected in circuit with the slide solenoid 13. Carried at one end of the rear carrier arm 68 is a pin 80 which, in a particular angular position of the arm, is adapted to coact with a leaf spring 81 on which there is carried the movable contact 82 of a switch 83 included in circuit with the oscillating solenoid 11.

The mechanism for actuating the several component parts of the selector unit in timed relation will now be described in connection with Figs. 11 and 12 which illustrate diagrammatically the cooperative relation between said parts. Arranged around the ring gear 27 are the solenoid-actuated gears 36 to 39. Normally these gears do not mesh with the ring gear, the latter being continuously rotated so long as the motor drive is effective. The normal inoperative position of solenoid gears 36 to 38 is shown in Fig. 12. Attached to the armature of the drum solenoid 12 is a spindle 84, the end adjacent the solenoid carrying the gear 37 and its opposite or outer end protruding through an aperture in the rear plate 16. The armature of the solenoid 13 which actuates the segregating bar carrier arms has the gear 38 attached thereto which is adapted when actuated to mesh with a gear 38' mounted at one end of a spindle 85 journaled in the plates 15, 16. A similar gear 38' is mounted at the other end of spindle 85, and in mesh with gears 38', 38" are the respective cam gears 73, 74. The armature of the solenoid 11 which oscillates the disc stack assembly is also provided with a spindle 86 journaled in the plates 15, 16, the end adjacent the solenoid carrying the gear 36 and the opposite end carrying the gear 36'.

In initiating operation at the remote control point, as by setting a rotary switch or pushing a button, the drum solenoid 12 is first energized so that the tendency of its shaft or spindle 84 is to move to the left, as viewed in Fig. 12. But this action is restricted by reason of the arcuate extension 69 on the carrier arm 67 (see Fig. 8) which in the first instance is in a raised position. The gear 37 is, therefore, prevented at this time from meshing with ring gear 27. The spindle 84 will, however, be permitted to move sufficiently to the left to close the contacts of switch 78 (see Figs. 9 and 18) which is included in the circuit of solenoid 13. The latter will now be energized to cause the shifting of the solenoid gear 38 to the left, as viewed in Fig. 12, into meshing engagement with both the ring gear 27 and the right hand gear 38". As a consequence, gears 73, 74 will be driven from the ring gear and the cams 75 will rotate to coact with the upright arm extensions 70 so that the slide bar carrier arms 67, 68 will be swung downwardly about their pivots 66. During the initial movement of the carrier arms, the extension 69 will be withdrawn to permit the gear 37 associated with the drum solenoid 12 to complete its axial movement to the left, thereby permitting meshing engagement between gear 37 and ring gear 27 and also with a gear 37' carried by the selector drum 41. As a result the drum will be caused to rotate until it arrives at a position determined by a homing switch 87 (shown diagrammatically in Fig. 10) movable with the drum, to be described more fully in connection with the schematic circuit diagram of Fig. 18.

The function of crown cam 76 is to raise pin 78 to circuit closing position even beyond the point where it is raised by spindle 84 upon energization of drum solenoid 12, thus keeping slide bar sole-

noid 13 energized while crown cam 76 is making a complete revolution, even though drum solenoid 12 has become deenergized because of the homing switch having found its open circuit.

The selector drum and slide bar operate in a definite timed relation. The gear ratio of the several gears associated with solenoids 12 and 13 is so chosen that the speed with which drum 41 rotates is twice the speed with which gears 73, 74 rotate. Therefore, once gears 73, 74 have started to rotate and the slide bar is withdrawn, drum 41 is able to make a complete revolution and come to rest before gears 73, 74 and their associated cams have made their complete revolution.

As previously described, the particular angular position at which the drum 41 is stopped determines which one of the key levers 40 is to be effective in bringing about the automatic adjustment of the disc stack assembly to a predetermined position. Upon completion of one revolution of the cams 75, the carrier arms will be returned to an upward position by action of the spring 71, and the segregating or slide bar 65 will be caused to ride under the tail end of the raised key lever and above the tail ends of the remaining levers, as previously described with reference to Figs. 7A to 7C. The head portion 59 of the key lever will now ride on the periphery of the associated disc, and in the position of the carrier arms which permits this, the pin 80 on the rear carrier arm 68 (Fig. 9) will force the spring leaf 81 upwardly to close switch 83. As a result, oscillating solenoid 11 will be energized and spindle 86 will move axially to the left, resulting in gear 36 at the right being driven from ring gear 27 and the gear 36' at the left meshing with a gear 88 carried on the rear plate 16. Through the medium of suitable means actuated by gear 88, the disc stack assembly is oscillated back and forth until the peripheral notch in the selected disc is brought into locking engagement with the operated key as previously described with reference to Figs. 7A to 7C. With the key seated or locked in engagement with its disc, the segregating bar is urged to move upwardly still further by action of its spring 71, and pin 80 being movable with the segregating bar moves out of engagement with spring leaf 81 to break the circuit through solenoid 11 thereby stopping operation of the oscillating means.

The arrangement whereby the disc stack and condenser are made to oscillate is shown in Fig. 13. The second small pinion 36' mounted on the spindle of solenoid 11 engages the gear 88 as mentioned above in connection with Fig. 12. An eccentric pin 89 carried on the gear supports one end of a connecting link 90 which has its other end pivotally mounted on a gear segment 91 at point 92. The gear segment itself is pivoted at 93 on rear plate 16 and meshes with the gear 55 which is associated with the stack assembly (Fig. 4). It will be seen therefore that while solenoid 11 is energized, gear 88 will rotate to drive the connecting link back and forth, which in turn will oscillate gear segment 91, pinion 55 and eventually the disc stack and the condenser associated therewith. Through the medium of disc 56 which is rigidly attached to gear 55 and friction drive 57 which is rigidly attached to gear 49 of the stack assembly, the driving relation between the crank gear 86 and the stack is a friction drive and therefore not entirely positive, thus permitting the oscillating drive to urge the stack and condenser to oscillate slightly more than 180 degrees, although it cannot do so because of limiting stops on the condenser. This

prevents a power build-up from the driving motor through to the condenser which might jam when a key is seated into a disc notch.

In order to initially adjust the mechanism to an automatic position the set-up lever 8 (Figs. 1 and 14) is first pulled forwardly which can be done conveniently with a finger of the left hand. Pulling this lever rotates the shaft 7 which carries a link member 94 as a crank arm. Attached to link 94 is a link 95 which moves rearwardly and axially to the stack shaft 17 and in turn causes a yoke 96 to swing rearwardly by reason of its arms being pivoted on a pair of pins carried on a fixed support, only one of which is shown at 97'. Yoke 96 carries the rollers 52, previously mentioned, which due to manipulation of lever 8 presses against disc 45 of the stack assembly, depressing the spring 46 and relieving the clamping of discs 42. At the time this lever is operated one of the automatic positions has been selected, and therefore one of the discs 42 is rigidly held in position. At this time the knob or hand wheel 5 (Figs. 1 and 14) attached to a shaft 97 is rotated and, through the medium of a gear 98 mounted thereon, an idler 99 mounted on a slide 100, and idlers 101 and 101', drives gear 49 of the stack assembly, thus rotating the tuning condenser and all the discs of the stack except the one that has been engaged by a key. Upon release of lever 8 the driving relation between shaft 97 and the stack is removed, and the pressure on the several discs 42 is restored to clamp them all to the stack.

The yoke 96 carries a pin 102 which is adapted to be received between a pair of disc plates 103 forming a part of the slide 100 on which the idler 99 is mounted. As shown more clearly in Fig. 15, which is a view in cross-section taken on line 15-15 of Fig. 14, the slide is movable on a shaft 104 which carries a guide pin 105 extending through a slot 106 in the slide. Between said pin and a second pin 107 carried by the slide there is connected a coiled spring 108 which tends to retain the slide in a forward position, as viewed in Fig. 14, or to the right as viewed in Fig. 15.

It will be seen, therefore, that simultaneously with the rearward movement of the yoke 96, due to the manipulation of the set-up lever 8, the slide 100 will be moved rearwardly due to its engagement with the pin 102 to bring idler 99 into meshing relation with gears 98 and 101, as previously mentioned. The slide 100 carries on its forward end a gear 109 which in the normal position of the slide as shown in Fig. 14 meshes with a gear 110 carried on the manual control shaft 97.

The knob or hand wheel 5 is used for the dual purpose of setting up the automatic positions in the manner described above and of locally tuning the condenser in a manner now to be described when the mechanism is set for manual operation. The shaft 104 carries at its forward end a beveled gear 111 which meshes with a second beveled gear 112 carried at one end of a shaft 113 which is journaled in bearings 114, 115 (Figs. 1 and 3). The opposite end of shaft 113 carries a beveled gear 116 which meshes with a beveled gear 117 affixed to spline 6. When the set-up lever 8 is released and the knob 5 is rotated, it will be seen that spline 6 will be rotated through the gear train comprising the gears 110, 109, 111, 112, 116, and 117, and, through the medium of the flexible shaft 6' attached at one end to the spline 6 and terminating at its other end in a control

member at a remote control box, the receiver may be manually tuned from a remote point.

Shaft 113 carries a worm 118 which also may be rotated either locally by tuning knob 5 or remotely through the medium of the flexible cable 6'. Worm 118 engages a split worm gear 119, shown in Figs. 1 and 17, mounted at one end of a shaft 120, on the other end of which there is carried a split gear 121 which is adapted to drive the shiftable disc assembly 47', previously mentioned with reference to Fig. 4, so that the latter may be rotated in response to either of the manual controls.

The shiftable manual disc assembly 47' comprises a ring gear 123 which is adapted to mesh with split gear 121 and is force fitted or otherwise attached to a disc member 124 having a peripheral surface 124' of the same diameter as discs 42 of the stack and a second peripheral surface 124'' of slightly reduced diameter. The assembly is further provided with a hub member 125 having a circular groove 125' formed in its periphery and a tapered pin 126 carried by disc 124 on its side facing the end disc 47. A coiled spring 126' concentrically arranged on the reduced end of shaft 17 between hub 125 and plate 15 tends to urge the disc assembly 123-125 towards the end disc 47, to the left as viewed in Fig. 17. In order to permit shifting of the disc assembly towards the end disc and to return the same to the disengaged position shown in Fig. 17 and to retain it in that position, there is provided a forked lever 127 pivoted at points 127'. The forked end 128 of the lever is disposed within the groove 125' of hub 125 and its opposite end is provided with a rearwardly projecting arm 129 and a downwardly projecting formed part 130 which is adapted to be engaged by a pin 133 attached to the carrier arm 67 at the front of the unit.

An 11th key 131 (Figs. 8, 16 and 17), similar to the 10 automatic keys 40 and also mounted on key shaft 58, is associated with the shiftable disc assembly and with the retaining and shifting lever 127. The key is provided at its tail end with a headed rivet 132 which is adapted to engage arm 129 of the shifting lever. During the automatic operation of the selector mechanism the 11th or manual key will assume the position shown in Fig. 16 by reason of its spring 64' which is similar to the several springs 64 individually associated with the several automatic keys 40. In that position the rivet 132 at the tail end of the key will engage arm 129 of lever 127 and the head end will be raised slightly above the periphery 124' of disc 24.

When it is desired to condition the selector mechanism for manual operation, the control switch at the remote point, to be described later in connection with Fig. 18, is set to a manual position. As a result, the selector drum is rotated to a position whereby its 11th projection 62' is effective to move the 11th key about its shaft in a clockwise direction. This key movement causes the rivet 132 to become disengaged from arm 129 and causes also the head end of the key to ride on the disc periphery 124'. The disengagement of arm 129 permits the axial shifting of disc assembly 123-125 towards end disc 47 due to the action of spring 126', and the disposition of the key head on 124' initiates operation of the oscillating mechanism for the stack assembly 19 in a manner similar to that brought about by the 10 automatic position keys. Unless the stack assembly happens to be in a

position such that the elongated slot 48 in end disc 47 is aligned or in registry with pin 126, the stack assembly is oscillated through its range until such alignment takes place whereupon the pin is caused to drop into the slot. The additional shifting movement of the disc 124 brought about by the pin dropping into the slot is sufficient to cause the 11th key to drop from the larger periphery 124' to the smaller periphery 124'' so that, in a manner analogous to an automatic key being wedged into a disc notch, operation of the oscillating mechanism is stopped by opening the circuit of oscillating solenoid 14 at switch 83.

With the shiftable disc assembly 123-125 locked in engagement with the disc stack and the split gear 121 being continuously in mesh with the ring gear 123, a mechanical drive is established between worm 118 and the stack to permit thereby direct tuning of the condenser either by knob 5 locally, or by way of the flexible cable 6' from a remote control box.

In the locked position between the shiftable disc assembly and the stack the segregating bar 65 is in its uppermost or initial position as shown in Fig. 7C. Subsequent operation of the remote control switch to recondition the selector mechanism for automatic operation causes the segregating bar carrier arms 67, 68 to swing downwardly about their pivotal points as described previously with reference to the cycle of operation for automatic selection. With the removal of the segregating bar from underneath the tail end of the 11th key, the spring 64' exerts sufficient pressure to lift the head end of the key clear of disc 124 and to lower the tail end so that its rivet will be in a position to receive the shifting lever arm 129. Continued downward movement of the carrier arms causes the pin 133 on arm 167 to engage the formed part 130 of lever 127 to force the latter to swing about its pivots, the forked part 128 moving the disc assembly away from the stack in opposition to spring 126' and the arm 129 moving towards rivet 132 to be engaged thereby. The locked engagement between parts 129 and 132 enables the shifting lever 127 to retain the disc assembly out of coupling engagement with the disc stack as shown in Fig. 17, and this condition will continue as long as the remote control switch is set to any one of the automatic positions and until the control switch is set to a manual position for operating the 11th key to effect the coupling engagement between the shiftable disc assembly and the disc stack as explained above.

The operation of solenoid 14 is a distinctly separate function from the others. It is energized only when a change in band is required. The pinion 39 on its shaft is adapted to engage ring gear 27 to drive a shaft 134 which carries at its rear end a beveled gear 135 and at its forward end the band dial 25 (Fig. 2). Bevel 135 engages a second bevel 136 attached to a disc 137 which carries a pin 137' near its periphery. A slide rod 138 is connected between the pin 137' and suitable actuating means 138' for the band-switch (not shown) which is located in the receiver proper. A homing switch 139 movable with the band-switch and also operated by the slide rod completes the circuit through the band-switch solenoid 14 keeping it energized until the slide rod has shifted sufficiently to cause selection of the proper band called for by the homing switch. Simultaneously the dial 25 will be rotated to a 75 position corresponding to the selected band, and

an indication thereof will be viewed through a suitable opening in the front panel of the selector device.

The electrical system of the selector mechanism above described is shown in Fig. 18. A control box 140 located at a remote point contains a pair of rotary selector switches 141, 142 arranged in tandem, and with their respective movable arms 143, 144 mounted on a common shaft represented by the dotted line 145. Switch 141 is provided with contacts 1 to 10, representing automatic positions, which are connected individually by way of conductors of the cable 9 to correspondingly numbered brush contacts of a switch wafer 87', said switch being further provided with contacts A to D, representing manual positions, which are connected together and to an 11th conductor 11' of the cable 9 which is connected to the brush contact 11 of the same wafer. The second switch 142 is provided with contacts A' to D' angularly disposed like contacts A to D and connected individually by way of cabled conductors 146 to 149 to a switchboard 150 housed in the upper part of casting 1, the remaining contacts of the switch being blank.

It will be understood, of course, that in place of the rotary selector switches 141, 142 there may be employed a system of push-buttons which would accomplish the same result.

The above-mentioned wafer 87' and wafers 87'', 87''' constitute the homing switch 87 mentioned previously and shown schematically in Fig. 10. Switch wafer 87' consists of a conducting ring 151 provided with a cut-out or insulating portion 152 at one point in its periphery, and the switch wafers 87'' and 87''' consist each of a conducting ring 153 which is provided with a projection 154. The three switch wafers are mounted on a common shaft, and the two projections 154 and the portion 152 are phased as shown to assume the same angular position with rotation of the switch wafers.

The brush contacts 1-12 associated with wafer 87' are adapted to contact the ring 151, the brush contact numbered 12 of this wafer being connected to the drum solenoid 12. The brush contacts 1 through 11 of the second wafer 87'' are connected to the correspondingly numbered brush contacts of wafer 87' and are out of contact with the ring 153, but are adapted to contact successively with the projection 154 upon rotation thereof. The brush contacts 1 through 10 of switch wafer 87''' are out of contact with its ring 153, but are adapted to contact successively with the projection 154 upon rotation thereof. The brush contacts 12 of the wafers 87'' and 87''' are in contact with their respective rings 153 and are electrically connected together. The contact brushes 1 through 10 of switch wafer 87''' are connected respectively with terminals 1' through 10' of the band selector switchboard 150.

The switchboard 150 is provided with a plurality of conductors, equal to the number of bands for which the receiver is designed, shown by way of example in the present embodiment as four bands and referred to hereinafter as the A, B, C and D bands. Said conductors may constitute extensions of the conductors 146 to 149 connected to switch 142 and are, therefore, similarly referenced. Each conductor has associated with it a plurality of contacts 155 which are aligned with the terminal contacts 1' to 10' and which are equal in number to the stations that are desired to have tuned-in automatically, there being 10 in the present embodiment. By means of a flexible lead 156 from each of the terminal

contacts 1' to 10' the latter may be selectively connected to any one of the aligned contacts 155 of the conductors 146 to 149.

The switchboard conductors 146 to 149 each terminate respectively at one of the brush contacts A' to D' which are associated with a wafer 157 of the homing switch 139, the wafer consisting of a conducting ring 158 provided at one point in its periphery with a cut-out or insulating portion 159. The wafer 157 of the band homing switch does not move in unison with the homing switch 87 for station selection but is moved independently when required by the band-switch solenoid 14 which is electrically connected to the brush contact 14 in contact with the ring 158.

A suitable source of energy for operating the mechanism is shown at 160. The + terminal of the source is connected through a motor relay 161 and then by way of a conductor 162 to the conducting shaft 145 of switches 141, 142, and by way of a conductor 163 to slide solenoid 13 and oscillating solenoid 11 through, respectively, switches 79 and 83, previously described. A motor 164 is connected between the terminal of the source and ground through a grounded relay armature 165 when pulled up to the front contact 166 of the relay, the armature normally resting on the relay back contact 167.

The manner of automatic operation of the selector will now be described. At the remote control box the switch arm 143 will be adjusted to any desired position 1 through 10, let us say to the position 9, as shown, which corresponds to station No. 9. The circuit completed thereby will be from the terminal of the power source, through motor relay 161, conductor 162, shaft 145, switch arm 143, contact 9, contact brush 9 of switch wafer 87', contact brush 12, drum solenoid 12, and to ground which is the negative side of the power source. As a result the motor relay 161 will pull up its armature to front contact 166 thereby closing the energizing circuit of operating motor 164 which begins to drive the ring gear 27. In actuating its armature to close the motor circuit the relay simultaneously breaks the cathode return circuit at contact 167 of one of the stages in the receiver, such as the second intermediate frequency (I. F.) stage, to thereby disable the receiver and to provide silent tuning during the automatic operation of the tuning mechanism.

The drum solenoid 12 is also energized with the completion of the above circuit, but as previously explained the selector drum is not yet actuated due to the stop 69 on carrier arm 67 being in the path of gear 37 which prevents it from engaging with the ring gear. The immediate effect of solenoid 12 upon its energization is to close the switch 79 thereby completing the circuit for slide solenoid 13 which actuates the slide bar 65 through its cycle of operation as previously explained. With the initial movement of the slide bar the stop 69 is withdrawn to permit the drum solenoid gear 37 to effectively couple the selector drum to the ring gear. The drum will now begin to rotate as will also the homing switch 87 which is mechanically coupled thereto. Upon the arrival of the homing switch wafer 87' to the position shown, the circuit of the drum solenoid will be broken at the brush contact 9 and the drum will stop at a position such that its projection 62 corresponding to station No. 9 will arrive underneath the key lever 60 associated therewith, as shown in Fig. 7B.

Unless the head 59 of the key lever seats itself in the notch of the corresponding selector disc 42 the switch 83 will be closed by the pin 80 and the oscillator solenoid 11 will be energized to allow its gears 36, 36' to mesh respectively with the ring gear and the gear train previously described for effecting the back and forth movement of the disc stack assembly until the key head drops into the notch of the selector disc corresponding to station No. 9, whereupon the pin 80 will be moved away from its engagement with spring contact 81 to permit switch 83 to open so that oscillating solenoid 11 will be de-energized.

In the position of the switch wafer 87''' of the homing switch a circuit will be closed from the + terminal of the energizing source, motor relay 161, conductor 162, shaft 145, switch arm 143, contact 9 of switch 141, brush contact 9 of wafer 87''' ring 153 and brush contact 12 of the same wafer, brush contact 12 of wafer 87''' ring 153 and brush contact 9 of the same wafer, terminal 9' of the switchboard 150, flexible conductor 156, conductor 146, brush contact A'' of homing switch wafer 157, ring 158 and brush contact 14' of said wafer, and band switch solenoid 14. The circuit above traced will then be closed to energize the band switch solenoid to cause the shifting of its gear 39 into coupling relation with the ring gear 27 to effect movement of the band switch and the homing switch 139 through the intermediary of elements 134, 135, 136, 137, 137' and 138 described and shown in connection with Fig. 2. Upon the arrival of homing switch wafer 157 to the position shown (Fig. 18) the circuit of band switch solenoid 14 will be broken at the brush contact A'', and the band switch of the receiver will have been rotated to the position required to adjust the receiver for station No. 9 which, due to the switchboard connection, is in the A band.

If, however, the terminal 9' at the switchboard had been connected by means of the flexible conductor 156 to, let us say, contact 155 on conductor 148 (which corresponds to the C band) the band switch would have been actuated by the solenoid 14 to a position such that the switch wafer 157 would be moved to a position in which its insulating portion 159 would be opposite the brush contact C'', in which position the circuit of solenoid 14 would be broken and the band switch set to band C.

It will be clear, however, that in automatically tuning the receiver from one station to another in the same band, as for example from No. 9 to No. 5, both being set up in switchboard for band A, the band switch solenoid 14 will remain inoperative, its circuit being open at brush contact A'' of homing switch wafer 157, and the band switch at the receiver will remain idle, that is, it will be set to the previously actuated band A position.

Other of the stations 1 to 10 may be tuned in automatically in a similar manner as explained above by merely selectively adjusting switch arm 143 at the remote control box on one of the contacts 1 through 10. The connections that are made in advance at the switchboard determine the particular band in which the respective stations are located. For example, station No. 1 is in band A, station No. 2 is in band C, station No. 4 is in band B, station No. 8 is in band D, etc.

Alternatively, as heretofore mentioned, the device may be conditioned for manual control from either the remote point or locally at the receiver. In accomplishing this the switch arm 143 at the

remote control box is moved to any one of the contacts A to D, depending upon the particular band within which it is desired to operate the receiver. In any case there will be completed a circuit similar to that described above in connection with contact 9 to energize the drum solenoid and effect rotation of the selector drum to the position where its 11th projection 62' will actuate the 11th or manual key lever 131 to initiate the shifting operation of the disc assembly 123-125 previously described with reference to Figs. 16 and 17. Upon completion of the shifting operation a direct mechanical coupling will be provided between the disc stack assembly and the worm 118 (Figs. 1 and 17) which permits the tuning device of the receiver to be actuated either by manual control knob 5 at the receiver or by a manual control 168 attached to the end of flexible cable 6' which terminates at the remote control box 140 or at an auxiliary control box.

In moving switch arm 143 to one of the manual positions A to D, switch arm 144 moving in unison therewith will contact the corresponding contact A' to D'. If it be assumed that manual tuning is desired to be had in the C band, for example, switch arm 144 will be moved to its contact C' to thereby close the following circuit: + terminal of source 160, motor relay 161, conductor 162, shaft 145, switch arm 144 which is now on contact C', conductor 148, brush contact C'' of wafer 157, conducting ring 158, brush contact 14' to band switch solenoid 14. As a result both motor 164 and solenoid 14 will be energized, the former driving the ring gear 27 and the latter shifting its coupling gear 39 to mesh therewith, thereby operating the actuating bar 138 for the band-switch and the homing switch 139 as previously explained (Fig. 2). Upon rotation of homing switch wafer 157 to the position where its insulating or cut-out portion 159 is opposite brush contact C'' the above described circuit will be broken. Solenoid 14 and motor 164 will then be de-energized and the band-switch at the receiver will be adjusted to its C position, as desired.

It should be noted that there may be incorporated in the selector mechanism one or more additional solenoids, such as the solenoid 14 for example, for accomplishing other independent functions, such as band-width control, which may be associated or disassociated with the sequence described above.

Although the invention has been described with particular reference to radio receiving apparatus it will be apparent to one skilled in the art that the invention may be applied equally as well to transmitters or other apparatus in which it is desired to automatically adjust the settings of variable devices from a remote point, or to accomplish other functions such as the selective switching of elements, etc.

While I have shown a particular embodiment of my invention, it will, of course, be understood that I do not wish to be limited thereto, since various modifications may be made both in the circuit arrangement, in the instrumentalities, and in the mechanical construction employed without departing from the spirit and scope of my invention as set forth in the appended claims, and I contemplate by the appended claims to cover any such modifications as fall within the true spirit and scope of my invention.

What I claim is:

1. Shaft positioning apparatus comprising, in combination, a shaft to be positioned, a stop-disc assembly mounted on the shaft comprising a plurality of stop-discs each of which corresponds to a different desired angular position of the shaft, a selector drum having a plurality of projections corresponding to the number of stop-discs, a series of keys cooperatively related with both said stop-disc assembly and said selector drum, each key being individually actuated by a separate drum projection for engagement with a corresponding individual stop-disc, driving means for said apparatus, individual means for coupling the selector drum and the stop-disc assembly to be driven independently from said driving means, and means for actuating said individual coupling means in a predetermined sequence of operations for actuating a selected key and for moving the corresponding stop-disc into locking engagement therewith for setting said shaft in desired angular position.

2. Shaft positioning apparatus in accordance with the invention defined in claim 1 wherein a unidirectional motor is utilized to actuate the driving means, and the means for actuating the stop-disc assembly from said driving means includes means for alternating the direction of rotation of said assembly.

3. Shaft positioning apparatus in accordance with the invention defined in claim 1 wherein the individual coupling means are electrically operated.

4. Shaft positioning apparatus comprising, in combination, a shaft to be positioned, a stop-disc assembly mounted on the shaft comprising a plurality of stop-discs each of which corresponds to a different desired angular position of the shaft, a series of keys each cooperatively related with a corresponding stop-disc, a selector drum constructed and arranged to select the particular key to be effective, a slide bar for actuating the selected key into locking engagement with its corresponding stop-disc, driving means for said apparatus, individual means for coupling the selector drum, the stop-disc assembly and the slide bar to be driven independently from said driving means, and means for actuating said individual coupling means in a predetermined sequence of operations for selecting and then actuating a particular key and for moving the corresponding stop-disc into locking engagement therewith for setting said shaft in desired angular position.

5. Shaft positioning apparatus in accordance with the invention defined in claim 4 wherein the slide bar has associated with it a stop member which, until the slide bar has been moved by actuation of its coupling means, prevents the actuation of the selector drum coupling means.

6. Shaft positioning apparatus comprising, in combination, a shaft to be positioned, a stop-disc mounted in adjusted relation on the shaft to be positioned, a key disposed in cooperative relation with said stop-disc, a cam device for moving the key towards the stop-disc to a limited extent, a slide bar for moving the key into engagement with said stop-disc, and means for driving said cam device to effect the limited movement of said key, and for driving said slide bar to effect a further movement of said key, and for driving said stop-disc into locking engagement with said key for setting said shaft in desired angular position.

7. Shaft positioning apparatus comprising, in combination, a shaft to be positioned, a stop-disc

mounted in adjusted relation on the shaft to be positioned, a key disposed in cooperative relation with said stop-disc, a cam device for moving the key towards the stop-disc to a limited extent, a slide bar for moving the key into engagement with said stop-disc, a common driving means, means for coupling said cam device to said driving means to effect the limited movement of said key, means for coupling said slide bar to said driving means to effect a further movement of said key, and means for coupling said stop-disc to said driving means for moving said disc into locking engagement with said key for setting said shaft in desired angular position.

15 8. Shaft positioning apparatus in accordance with the invention defined in claim 7 wherein each of the several coupling means consists of a gear which normally is disengaged from the driving means, and each gear is shifted in timed relation 20 by means of a solenoid having its armature affixed to the gear.

25 9. Shaft positioning apparatus in accordance with the invention defined in claim 7 wherein the slide bar has associated with it a stop member which, until the slide bar has been moved by actuation of its coupling means, prevents the actuation of the coupling means associated with the cam device.

30 10. Shaft positioning apparatus comprising, in combination, a shaft to be positioned, a stop-disc mounted in adjusted relation on the shaft to be positioned, a key disposed in cooperative relation with said stop-disc, a selector drum 35 for moving the key towards the stop-disc to a limited extent, a slide bar for moving the key into engagement with said stop-disc, a carrier for the slide bar, a cam for actuating the slide bar carrier, a common driving means, 40 means for coupling said drum to said driving means to effect the limited movement of said key, means for coupling said slide bar cam to said driving means to effect a further movement of said key, means movable with said cam for making the slide bar coupling means effective prior to the drum coupling means, and means for coupling said stop-disc to said driving means for moving said disc into locking engagement with said key for setting said shaft in desired angular position.

50 11. Mechanism for automatically and selectively adjusting a device to one of a plurality of predetermined positions, comprising a plurality of stop-discs movable with the device each corresponding to one of said positions, a plurality of locking keys each adapted to cooperate with a corresponding stop-disc, key selector means operative to select the particular key which is to be effective, key actuating means for moving the selected key into operative relation with its corresponding stop-disc, an electric motor, a master gear driven by the motor, and means for actuating the key selector means, the key actuating means and the plurality of stop discs from the master gear in proper sequence whereby the key selector means is first operated to a predetermined position to select a particular key, after which the key actuating means is operated to cause the selected key to rest on the periphery of its associated stop-disc, and then said stop-disc is moved into locking engagement with the selected key at which time the device will assume its predetermined adjusted position.

65 12. Mechanism for automatically and selectively adjusting a device to one of a plurality of predetermined positions, comprising a plurality of

75

of stop-discs movable with the device, each corresponding to one of said positions, a plurality of locking keys each adapted to cooperate with a corresponding stop-disc, key selector means operative to select the particular key to be effective in determining the desired adjusted position of the device, key actuating means for moving the selected key into engagement with its corresponding stop-disc, and electric motor, a master gear driven by the motor, means for individually coupling the key selector means, the key actuating means and the stop-discs to the master gear to be driven therefrom, and means for making the individual coupling means effective in proper sequence whereby the key selector means is first operated to a predetermined position to select a particular key, after which the key actuating means is operated to cause the selected key to move into engagement with its associated stop-disc, and then said stop-disc is moved into locking engagement with the selected key at which time the device will assume its predetermined adjusted position.

13. Mechanism in accordance with the invention defined in claim 12, wherein the motor is of the unidirectional type, and the means for driving the stop-discs includes means for oscillating the discs back and forth until locked in position by a key.

14. Mechanism in accordance with the invention defined in claim 12, wherein a friction clutch is interposed between the stop-discs and the driving means therefor.

15. Mechanism in accordance with the invention defined in claim 12, wherein the individual coupling means are electrically operated.

16. Mechanism in accordance with the invention defined in claim 12, wherein the coupling means each includes a gear normally disengaged from the master gear, and there is provided a solenoid having its armature attached to said gear so that upon energization thereof the gear is shifted into meshing relation with the master gear.

17. Mechanism for automatically and selectively adjusting a device to one of a plurality of predetermined positions from a remote control point, comprising a plurality of stop-discs movable with the device each corresponding to one of said positions, a plurality of locking keys each adapted to cooperate with a corresponding stop-disc, key selector means operative to select the particular key to be effective in determining the desired adjusted position of the device, key actuating means for moving the selected key into engagement with its corresponding stop-disc, an electric motor, a master gear driven by the motor, means including solenoid-actuated gears for individually coupling the key selector means, the key actuating means and the stop-discs to the master gear to be driven therefrom, and a multi-position switch at the remote control point having positions corresponding with those to which the device is to be adjusted, said switch upon manual adjustment to a desired position being adapted to energize the motor and said gear actuating solenoids in proper sequence whereby first the key selector means is operated to a predetermined position to select a particular key, after which the key actuating means is operated to cause the selected key to move into engagement with its associated stop-disc, and then said stop-disc is moved into locking engagement with the selected key at which time the device will assume its predetermined position of adjustment

corresponding to the position of the remote control switch.

18. Shaft positioning apparatus comprising, in combination, a shaft to be positioned, a manual control member selectively settable to one of a plurality of positions which correspond to automatic shaft-positions or to one or more positions which correspond to manual shaft-positions, a disc stack assembly coupled to the shaft comprising a plurality of discs corresponding to automatic shaft positions, manually-operated adjusting means for the shaft, an additional disc corresponding to manual shaft-positions adapted to be actuated by said manually-operated means, a plurality of selector keys each adapted to cooperate with a corresponding automatic disc, means operative automatically in response to the manual control member being set to an automatic position to operate a corresponding automatic selector key for effecting adjustment of the disc assembly, an additional selector key adapted to cooperate with the manual disc, and means operative automatically in response to the manual control member being set to a manual position to make the plurality of automatic selector keys ineffective and simultaneously to operate the additional selector key for providing a coupling engagement between the manually-operated adjusting means and the disc stack assembly.

19. Shaft positioning apparatus comprising, in combination, a shaft to be positioned, a manual control member selectively settable to one of a plurality of positions which corresponds to automatic shaft-positions or to one or more positions which correspond to manual shaft-positions, a disc stack assembly coupled to the shaft comprising a plurality of discs corresponding to automatic shaft-positions, manually-operated adjusting means for the shaft, an additional disc corresponding to manual shaft-positions adapted to be actuated by said manually-operated means, a plurality of selector keys each adapted to cooperate with a corresponding automatic disc, means operative automatically in response to the manual control member being set to an automatic position to operate a corresponding automatic selector key for effecting adjustment of the disc assembly, spring means tending to cause coupling engagement between said additional manual disc and the disc assembly, an additional selector key associated with the manual disc adapted in its inoperative position to make the spring means ineffective whereby the manual disc is uncoupled from the disc assembly, and means operative automatically in response to the manual control member being set to a manual position to make the plurality of automatic selector keys ineffective and simultaneously to move the manual selector key to its operative position whereby the manual disc under influence of the spring means is moved into coupling engagement with the disc assembly, thereby providing driving relation between the manually-operated adjusting means and the disc assembly.

20. Shaft positioning apparatus comprising, in combination, a shaft to be positioned, a manual control member selectively settable to one of a plurality of positions which correspond to automatic shaft-positions or to one or more positions which correspond to manual shaft-positions, a disc stack assembly coupled to the shaft comprising a plurality of discs corresponding to automatic shaft-positions, manually-operated adjusting means for the shaft, an additional disc corresponding to manual shaft-positions mechan-

ically coupled for rotation by said manually-operated adjusting means, a plurality of selector keys each adapted to cooperate with a corresponding automatic disc, means operative automatically in response to the manual control member being set to an automatic position to operate a corresponding selector key for effecting adjustment of the disc assembly, spring means tending to urge the additional manual disc into coupling engagement with the disc assembly, a member for retaining the manual disc disengaged from the disc assembly in opposition to the spring means, an additional selector key associated with manual disc adapted in its inoperative position to hold the retaining member in the disc-disengaged position, and means operative automatically in response to the manual control member being set to a manual position to make the plurality of automatic selector keys ineffective and simultaneously to move the manual selector keys to its operative position whereby the manual disc under the influence of the spring means is moved into engagement with the disc assembly, thereby providing driving relation between the manually-operated adjusting means and the disc stack assembly.

21. Shaft positioning apparatus in accordance with the invention defined in claim 20 wherein means are included which upon operation act to restore the retaining member to its disc-disengaged position.

22. Shaft positioning apparatus in accordance with the invention defined in claim 20 wherein means are included which upon operation act to restore the retaining member to its disc-disengaged position, said means being operative a short interval after the manual control member is moved to an automatic position from a previously set manual position.

23. Mechanism for automatically and selectively rotating an element to be adjusted to one of a plurality of predetermined positions, a homing switch movable with the element and provided with a plurality of brush contacts each corresponding respectively to one of said predetermined positions, a solenoid having its winding connected to the homing switch, a control switch having contacts each connected respectively to one of the brush contacts and having a movable arm connected to one terminal of a source of current, an electric motor connected to said source, a first gear driven by said motor, a second gear movable with the element to be adjusted, and a third gear movable with the solenoid-armature normally out of engagement with said first and second gears, the arrangement being such that upon adjustment of the control switch to a selected contact the motor is energized to drive the first gear and a circuit is closed through the solenoid to shift the third gear into coupling engagement with both the first and second gears whereby the latter serves to drive the element to be adjusted until the solenoid and motor circuits are broken by the homing switch being moved to a position determined by the setting of the control switch.

24. Mechanism for automatically and selectively rotating an element to be adjusted to one of a plurality of predetermined positions, a homing switch movable with the element and provided with a plurality of brush contacts each corresponding respectively to one of said predetermined positions, a solenoid having its winding connected to the homing switch, a control switch

having contacts each connected respectively to one of the brush contacts and having a movable arm connected to one terminal of a source of current through a relay, an electric motor connected to said one terminal of the source and to the other terminal through the relay-armature when actuated to circuit-closing position, a first gear driven by said motor, a second gear movable with the element to be adjusted, and a third gear movable with the solenoid-armature normally out of engagement with said first and second gears, the arrangement being such that upon adjustment of the control switch to a selected contact a circuit is closed through the relay to close the motor circuit thereby driving the first gear and another circuit is closed through the solenoid to shift the third gear into coupling engagement with both the first and second gears whereby the latter serves to drive the element to be adjusted until the circuits are broken by the homing switch being moved to a position determined by the setting of the control switch.

25. Mechanism for automatically and selectively rotating a first element to one of a plurality of predetermined positions and a second element to one of a plurality of predetermined positions which may be different in number than the positions of the first element, a pair of homing switches each movable with its respective element and provided with a plurality of brush contacts each corresponding respectively to one of said predetermined positions, a pair of solenoids each having a winding connected to its respective homing switch, a control switch having contacts each connected respectively to one of the brush contacts of one homing switch and having a movable arm connected to one terminal of a source of current, a switchboard connected between the first homing switch and the brush contacts of the second homing switch, an electric motor connected to said source, a master gear driven by said motor, a gear movable with each of the elements to be adjusted, and a gear movable with each of the solenoid armatures normally out of engagement with the master gear and with the element gear, the arrangement being such that upon adjustment of the control switch to a selected contact the motor is energized to drive the master gear and a circuit is closed through each solenoid to shift its respective gear into coupling engagement with both the master and element gears whereby the latter serve to drive their respective elements to be adjusted until the solenoid and motor circuits are broken by the homing switches being moved to their respective positions determined by the setting of the control switch and the switchboard connections.

26. Control mechanism for automatically and selectively adjusting a rotary device to one of a plurality of predetermined positions, a plurality of stop-discs movable with said device each corresponding to one of said positions, a plurality of locking keys each adapted to cooperate with a corresponding stop disc, key selector means operative to select the particular key to be effective in determining the desired adjusted position of the device, key actuating means for moving the selected key into engagement with its corresponding stop-disc, a homing switch movable with the key selector means adapted to determine the position to which said means is to be adjusted, a second multi-position device, each position of which may be correlated in a predetermined manner with the automatically adjusted

positions of the first device, means for actuating the latter homing switch, a switchboard interconnected between said two homing switches, the connections therein being selectively made in advance to correlate the adjusted disc positions with the various positions of the multi-position device, an electric motor, a master gear driven by the motor, means for individually coupling the key selector means, the key actuating means, the stop-discs and the second homing switch to the master gear to be driven therefrom, and means for making the individual coupling means effective in proper sequence whereby the key selector means is operated to a predetermined position to select a particular key, after which the key actuating means is operated to cause the selected key to move into engagement with its associated stop-disc, then the stop-disc is moved into locking engagement with the selected key, and the second device is actuated to its correlated operative position.

27. Remote control mechanism for automatically and selectively adjusting a rotary device to one of a plurality of predetermined positions, a plurality of stop-discs movable with said device each corresponding to one of said positions, a plurality of locking keys each adapted to cooperate with a corresponding stop-disc, key selector means operative to select the particular key to be effective in determining the desired adjusted position of the device, key actuating means for moving the selected key into engagement with its corresponding stop-disc, a homing switch movable with the key selector means adapted to determine the position to which said means is to be adjusted, a second device capable of adjustment to a plurality of positions each of which may be correlated in a predetermined manner with the automatically adjusted positions of the first device, a second homing switch movable with said second device, means for actuating the latter homing switch, a switchboard interconnected between said two homing switches, the connections therein being selectively made in advance to correlate the adjusted disc positions with the various positions of the second device, an electric motor, a master gear driven by the motor, means including solenoid-actuated gears for individually coupling the key selector means, the key actuating means, the stop-discs and the second homing switch to the master gear to be driven therefrom, and a multi-position switch at the remote control point having positions corresponding with those to which the first device is to be adjusted, said switch upon manual adjustment to a desired position being adapted to energize the motor and said gear actuating solenoids in proper sequence whereby the key selector means is operated to a predetermined position to select a particular key, after which the key actuating means is operated to cause the selected key to move into engagement with its associated stop-disc, then the stop-disc is moved into locking engagement with the selected key at which time said first device will assume its predetermined position of adjustment corresponding to the position of the remote control switch, and the second device is actuated to its correlated operative position.

28. Means for automatically and selectively rotating an element to one of a plurality of predetermined positions, a stop-disc assembly movable with the element to be adjusted, each stop-disc corresponding to one of said positions, a plurality of locking keys each adapted to cooperate

with a corresponding stop-disc, a selector drum operative to select a particular key to be effective, a segregating bar for moving the selected key into operative relation with its corresponding stop-disc, a homing switch movable with the selector drum provided with a plurality of brush contacts each corresponding respectively to one of said predetermined positions, a control switch having contacts each connected respectively to one of the brush contacts of the homing switch and having a movable arm connected to a source of energy, an electric motor connected to said source, a master gear driven by said motor, individual means each including a solenoid for actuating the selector drum, the segregating bar and the disc assembly from the master gear, and means responsive to actuation of the control switch for effecting a predetermined sequence of operation of the several solenoids whereby the selector drum is operated to a predetermined position to select a particular key, and the segregating bar is operated to cause the selected key to rest on the periphery of its associated stop-disc, and the disc assembly is moved to bring said stop-disc into locking engagement with the selected key in order that the element movable with the assembly may assume its predetermined position of adjustment.

29. Means for automatically and selectively rotating an element to one of a plurality of predetermined positions, a stop-disc assembly movable with the element to be adjusted, each stop-disc corresponding to one of said positions, a plurality of locking keys each adapted to cooperate with a corresponding stop-disc, a selector drum operative to select a particular key to be effective, a segregating bar for moving the selected key into operative relation with its corresponding stop-disc, a homing switch movable with the selector drum provided with a plurality of brush contacts each corresponding respectively to one of said predetermined positions, a control switch having contacts each connected respectively to one of the brush contacts of the homing switch and having a movable arm connected to a source of energy, an electric motor connected to said source, a master gear driven by said motor, individual means each including a solenoid for actuating the selector drum, the segregating bar and the disc assembly from the master gear, the winding of the selector drum solenoid being connected between the homing switch and the energy source, a first switch connecting the winding of the segregating bar solenoid to the energy source, a second switch connecting the winding of the disc assembly solenoid to the energy source, means responsive to actuation of the control switch for energizing the selector drum solenoid, means operative upon energization of the latter to prevent operation of the selector drum and to close the first switch to thereby energize the segregating bar solenoid for moving said bar to an inoperative position, means effective upon said movement of the segregating bar to permit operation of the selector drum to a predetermined position to select a particular key, means for effecting movement of the segregating bar to an operative position to cause the selected key to rest on the periphery of its associated stop-disc, and means adapted in said operative position of the segregating bar to close the second switch to thereby energize the disc assembly solenoid for actuating the disc assembly until said stop-disc is moved into locking engagement with the selected key in order that the element movable with

25

the assembly may assume its predetermined position of adjustment.
